UNITED STATES PATENT OFFICE.

THOMAS L. McKEEN, OF NEW YORK, N. Y., ASSIGNOR OF ONE-HALF TO
HARRY C. BLYE, OF SAME PLACE.

CAR-COUPING.

SPECIFICATION forming part of Letters Patent No. 539,286, dated May 14, 1895.

Application filed March 9, 1895. Serial No. 541,165. (No model.)

To all whom it may concern:

Be it known that I, THOMAS L. McKEEN, a citizen of the United States, and a resident of New York, in the county of New York and State of New York, have invented certain new and useful Improvements in Safety Attachments for Car-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a car-coupling of the so-called "Master Car-Builders" type provided with my safety attachment. Fig. 2 is a plan or top view of the same, showing various modifications in the location and arrangement of the safety device. Fig. 3 is a transverse sectional view of the end sill and buffer-block on the oblique vertical plane indicated by the broken line marked *xx* in Fig. 2, illustrating more clearly the construction and arrangement of the hooked bolt to which one end of the safety-link is fastened. Fig. 4 is a horizontal sectional view, on an enlarged scale, of the nutted end of said hooked bolt, with its attachments. Fig. 5 is a transverse sectional view through the draw-head on the vertical plane indicated by the broken line marked *yy* in Fig. 2. Fig. 6 is a detail view of the bent pin or bolt appertaining to the draw-head of the coupler as part of my safety attachment, and Fig. 7 is a detail view of the hooked bolt appertaining to the end sill and buffer-block of the car body.

Like letters of reference designate corresponding parts in all the figures.

My invention has for its object to provide a safety-attachment for car-couplings of the so-called "M. C. B." ("Master Car Builders") pattern, such as the "Janney," "Thurmond," "Standard," and other well-known couplings of the "knuckle" type, which are now coming into very general use on the railroads of the United States, as well as abroad. In couplings of this particular type, the drawhead is of necessity very large and heavy; and in hauling trains it sometimes happens that the draft rigging gives way, releasing the coupler;

or the head of the coupler breaks off in consequence of the sudden and violent contact by buffing; causing it (the broken-off drawhead) in either case to fall on the track, 55 which is liable to result in the derailment of the cars, stripping-off the brake-beams and doing other injury, whereby the lives of both passengers and trainmen are endangered, besides seriously damaging the cars and track, 60 causing delays in the running of trains, and other serious inconveniences. It will therefore readily be seen that it is of the utmost importance to provide means for the prevention of such accidents; and this I accomplish 65 effectually, yet in a very simple and inexpensive manner, by combining with the drawhead of the coupling the safety-link and attachments, which I shall now proceed to describe.

Referring to the accompanying drawings, the reference-letter A designates the end-sill of a railway car, the drawhead D of which is equipped with my safety-attachment. The buffer-block is shown at B, and the drawbar 75 at C;—both the drawhead and drawbar, D C, may be of any approved construction.

On the drawings, I have shown my safety-attachment as applied to a "Thurmond" coupler, the drawhead of which, back of the 80 knuckle, is cast with two registering or coinciding apertures, *a* and *b*, one in the roof and the other in the bottom of the interior recess within which the tail of the knuckle works. By preference the top aperture *a* is made 85 round and the bottom hole *b* square; but this arrangement may be reversed; or both apertures may be made square, if for any reason deemed advisable; the object being simply to prevent the bolt E, which is inserted vertically and removably through the apertures *a* and *b*, from turning. In this case, the bottom hole *b* is square, and the lower end of bolt E is also squared, as shown at *e*; its depending end, which projects below the aperture *b*, being provided with a key or cotter *e'* to hold it in place vertically; or the lower end may be screw-threaded and nutted for the same purpose. I prefer to use a cotter, however, as a nut is apt to jar off, unless constructed 95 with a nut-lock.

The bolt E is bent at right angles at its up-

per end, forming an elbow F, which projects horizontally and forwardly in a plane parallel to the axis of the drawbar, or at right angles to the end-sill and buffer-block of the car; 5 said projecting arm or elbow F being prevented from turning by the squared part of the bolt. Another bolt, G, is inserted in a horizontal plane obliquely through the buffer-block B and end-sill A, back of the buffer-block; the rearmost end of said horizontal bolt G being screw-threaded, and inserted centrally through a pillow-block or bolster I, (preferably of cast iron or other suitable metal,) of circular shape, but cut off slantingly or obliquely on one side or face, as shown at α , to conform to the angle or incline of bolt G relative to the buffer-block and end-sill, through which it is inserted horizontally but obliquely. Back of this bolster, I, is an ordinary metal disk-washer J, between which and another similar circular washer, K, is placed a stiff spring-washer L, made either of rubber or of metal (or it may be a "combination" rubber and steel spring); said disk-washers J 25 and K, with the spring L between them, being held in place upon bolt G by means of a nut M, which should be prevented from working loose by any approved form of locking-device applied to it.

30 The opposite or forward end of the horizontal bolt G is bent into a hook-shape, with its free limb H doubled upon itself in a parallel line, the end h of said limb H fitting into a recess h' bored in the front side of the buffer-block B, in vertical alignment with the oblique long bolt-hole g, which will prevent bolt G H from turning; care being taken to make the lip h long enough, and its recess h' deep enough, to prevent the lip from being pulled 35 out of its recess when the bolt is being pulled upon so as to compress its spring L to the greatest possible extent. A link, N, is slipped with one end over said hook H G, appertaining to the end-sill and buffer-block of the car-body, and with its other end over the hook or elbow, F, of the vertical bolt E e, appertaining to the car-coupling; and this link must be long enough to give the drawhead sufficient play (i. e., limit of motion, both forward 40 and back and to both sides) to work properly in starting and stopping a train, or in turning curves; permitting the coupling, in all respects, to work precisely as if there were no safety-attachment connected with it.

45 From the foregoing description, taken in connection with the drawing, the operation of my attachment will be understood at a glance. If the drawbar C should break and the drawhead D pulled out, it cannot possibly 50 drop to the ground, but will remain suspended from the solid and substantial timbers which form the end-sill and buffer-block of the car-body, by means of the hook-bolts E F and G H, in combination with the link N.

55 As the elbow F cannot turn, it is impossible 55 for the link to slip off or become disengaged from the drawhead D; and it is equally im-

possible for said link to become disengaged from the hooked bolt G H. The spring-washer L gives sufficient play, in a longitudinal direction, to the bolt G within its bolt-hole g to prevent any sudden jar or shock, which will be taken up by the spring-washer L acting as a cushion; and by means of the obliquely cut-off bolster I i, the bolt G though inserted obliquely or in a slanting direction through the timbers A and B (viz: the "end sill" and "buffer-block" of the car-body), will nevertheless take a true purchase or bearing against the same; the pull upon bolt G (in the event of accident,) when it has to support the broken-off drawhead being thus sustained by both the timbers A and B instead of one of them only.

It will be obvious, that the precise location 85 of the drawhead bolt E F, relative to the body of the drawhead, is unimportant, so long as it serves as a means for connecting said drawhead to the attachment link N in such a manner as to permit said link to operate in the 90 manner described.

As a matter of fact, the exact location of bolt E F, and the registering apertures a and b through which it is inserted, must and does depend upon details of construction of the 95 particular style of drawhead with which the safety-attachment is to be used; depending upon the disposition of metal and space, &c., which differs somewhat in the different styles and nomenclatures of coupling; all of which, however, conform to the same general "Master Car Builders'" pattern. Thus, for instance, in the "Thurmond" coupling it will be found most convenient to cast the holes a b in the body of the drawhead, back of the pivoted 100 knuckle; the vertical bolt E F occupying a position in the drawhead recess immediately back of the tail of the knuckle, as illustrated in full lines in the plan or top view, Fig. 2; whereas in the "Janney" style of coupling 105 (which is of the same general "Master Car Builders'" pattern), it will be found most convenient to locate bolt E F about centrally, or in alignment with the draw-bar C. The same arrangement would apply to the so-called 110 "Standard" coupling; while in other styles of 115 couplings of the same pattern, the vertical drawhead-bolt may be most conveniently located in the right horn or guard-arm of the drawhead, back of the lip, as indicated by 120 dotted lines on Fig. 2; and it will be obvious 125 that the location and arrangement of the horizontal bolt G H and link N must correspond to the locations of the drawhead-bolt E F; said bolt G H being placed either on the left side 130 of the drawbar, as shown in full line on the drawings; in alignment with and above the axis of the drawbar, centrally between the parallel draw-sills A' A'; or obliquely on the right-hand side of the drawbar, opposite to 135 the place where it is shown located on the drawings, but arranged in substantially the same manner, i. e., inserted obliquely through the end sill A and the buffer-block B, with a

bolster and buffer-spring, or spring-washer, back of the end sill, as shown in dotted lines.

Having thus described my invention, I claim and desire to secure by Letters Patent of the 5 United States—

1. The combination with the drawhead, D, of a car-coupling, of the vertically inserted bolt, E, having a right-angled arm or elbow, F, projecting above the top of the drawhead 10 in a plane approximately parallel to the axis of the drawbar, and provided with a squared section fitting into a square aperture in the body of the drawhead; link N, and hooked bolt G H, inserted through the buffer-block 15 and end-sill of the car, and provided with a nut M, and spring-washer, L, inserted between the nut and end-sill; substantially as and for the purpose shown and set forth.
2. The combination of the drawhead, D, 20 having apertures a b; bolt, E, having the right-angled elbow, F, and adapted to fit in the apertures, a b, so that it cannot turn therein; link N; hooked bolt, G, doubled upon itself to form the parallel limb, H, having lip, 25 h; end-timbers, A and B, bored through obliquely at g and having a recess, h', in verti-

cal alignment with said bore or bolt-hole; oblique bolster or bearing-block, I; nut M; and spring-washer, L; all constructed and combined to operate substantially in the manner and for the purpose herein shown and set forth.

3. The combination with the end-timbers of a car-body, and the coupling appertaining to the same, of the hooked bolt, G H, inserted 30 horizontally through said end-timbers and provided with a spring or cushion back of the same; the bolt E F, inserted vertically through the body of the drawhead and having an arm or elbow projecting above the same, in a plane 35 approximately parallel to the axis of the drawbar; and the link N, connecting the hooked bolts G H and E F; substantially as and for the purpose shown and set forth.

In testimony that I claim the foregoing as 40 my own I have hereunto affixed my signature in presence of two witnesses.

THOMAS L. MCKEEN.
